ATTORNEY

UNITED STATES PATENT OFFICE.

GUYON L. C. EARLE, OF FOREST HILLS, NEW YORK.

APPARATUS FOR RETURNING WATER OF CONDENSATION TO BOILERS, &c.

1,200,090.

Specification of Letters Patent.

Patented Oct. 3, 1916.

Application filed June 17, 1915. Serial No. 34,596.

To all whom it may concern:

Be it known that I, GUYON L. C. EARLE, a citizen of the United States, and a resident of Forest Hills, in the county of Queens and 5 State of New York, have invented certain new and useful Improvements in Apparatus for Returning Water of Condensation to Boilers, &c., of which the following is a specification.

10 The object of my present invention is essentially the same as that disclosed in my Letters Patent No. 1,121,339, issued Dec. 15, 1914, namely the provision of simple and effective means whereby drip of water of condensation, as for instance from a system of heating by steam, may be automatically and economically returned to the boiler. While 15 the result of experimental investigation with the apparatus disclosed in said Letters Patent, the present invention has a somewhat broader field of application and utility, being adaptable to the automatic return or raising of various liquids in the arts as well as to the return of condensed steam to a 20 boiler, by means of hydraulic pressure.

In the accompanying drawings, Figure 1, is a sectional elevation illustrating the essential features of my invention and the relative arrangement of component parts of 30 apparatus adapted to its practical application; Fig. 2, is a sectional detail upon a larger scale of a float valve adapted to automatically control the operation of my device, considered as a whole; Fig. 3, is a diagrammatic view in sectional elevation and dotted lines representing the parts at the completion of the retraction stroke of the pistons; Fig. 4, is a similar view showing the parts in position just prior to the actuating of the 35 automatic trip by which the motion of the pistons is reversed; Fig. 5, is an end elevation of the essential parts of the apparatus; Fig. 6, a transverse section taken upon plane of line 6—6, Fig. 4; Fig. 7, is an elevation of 40 the apparatus taken at the end thereof opposite that shown in Fig. 5.

C, is the collection cylinder which receives water of condensation or any other liquid from any source. We will presume herein 50 for convenience of illustrating the principle involved that the fluid to be collected and saved is the condensation of steam from a heating system, or the like, with the understanding that any other liquid may be thus received and returned or transferred, as may be found desirable or expedient in various

industrial arts. The drip enters the collection cylinder C, through a pipe c, which may be provided with a check valve c', to counteract back pressure. The discharge 60 from the collection cylinder C, is effected through the pipe or conduit c'', also provided with a check valve c''.

P, is the hydraulic power cylinder of equal length but usually of less diameter and area 65 than the collecting cylinder C, with which it is permanently related and positioned, preferably in alinement. The rod a, connects the power piston A', rigidly with the discharge piston A. Liquid pressure is applied to the power cylinder P, at the rear of its piston A', through conduit p, the forward end of which connects with the casting v, of the throttle valve V, interposed between said pressure conduit p, and the pressure pipe p', communicating with any source of liquid pressure, as for instance with a main pressure water supply pipe or the equivalent. The throttle valve V, is operated and controlled automatically by means 70 of a throttle lever v', and float v'', inclosed in the sealed auxiliary float chamber v'', communicating through the ducts v⁴, v⁵, with the collection chamber C, in such manner that when said cylinder C, fills with liquid 75 the float v'', acting through the throttle rod v', will move the valve V, from its seat and admit fluid pressure to the rear of the power cylinder P, through the conduit p. Attached to the rear side of the power piston A', is a flexible connection a'', which extends through a packed outlet p², in the rear end cap p³, of the power cylinder P, (as shown more particularly in Fig. 1,) and from thence over a pulley a'—said flexible connection being provided with a weight 80 w, which tends constantly to retract the power piston P. 90

d, is a discharge pipe leading from the rear of the power cylinder P, to a sewer or 100 elsewhere, as may be found most expedient. Interposed in this discharge pipe d, is a lever valve d'. In like manner a lever valve p⁴, is interposed in the power pipe p; and these two lever valves d', p⁴, are preferably 105 opposite in relation to each other,—the power pipe p, and the discharge pipe d, being parallel, or essentially so.

The valve levers p⁴¹, and d'', are pivotally connected by links p⁴², and d¹², with a 110 floating sleeve S, mounted loosely on the piston rod a. A compressible expansive

spring s^x , is interposed between this sleeve S, and the power piston A', of the power cylinder P, and tends constantly to press the forward end of the sleeve S, against a 5 shoulder or collar a^2 , on the fore part of the said piston rod a , as shown in Figs. 1, and 3. The sleeve S, at its rear extremity is formed with an annular collar s' , or equivalent shouldered structure, for engagement with 10 spring latch dogs e, e , pivotally mounted on the forward end of the cylinder P, or any other suitably positioned stationary supports.

The operation is as follows: At the completion of the forward stroke of the piston A, A', under liquid pressure exerted against the rear of the power piston A', the latter trips the latch dogs e, e , against the resistance of their springs e', e' , as in Fig. 1, 15 thereby releasing the sleeve S, so that it is free to be projected forward along the piston rod a , under the expansive force of the spring s^x , until its forward end rests against the shoulder a^2 , on said piston rod a . In doing so the sleeve S, by means of the connecting links p^{42} , and d^{12} , rocks the valve levers p^{41} , and d^{11} , so as to close the power inlet valve p^4 , and open the discharge valve d' , thereby relieving the pressure at the rear of 20 the power piston A', under which conditions the weight w , exerts itself to effect the retractile stroke of both pistons A, A', and rod a . As the power piston A', recedes from contact with the inner ends of the latch dogs e, e , the springs e', e' , of the latter return them to the positions shown in Figs. 3, and 25 4. As the sleeve S, by reason of its contact with the shoulder a^2 , of the piston rod a , is carried to the rear position it again releases the valves, opening the power valve p^4 , and closing the discharge valve d' , at the same time that the shoulders s' , on the sleeve automatically trip the latches e, e , and thereby lock the sleeve in the position shown in Figs. 3, and 4,—it being understood that the ports in the valves p^4 , and d' , are properly timed 30 in this respect. Thus at the completion of the retractile movement of the pistons, &c., the parts assume the relative positions shown in Fig. 3, and remain so until the water of condensation or other liquid to be conserved collects in the cylinder C, and casing v^3 , to a level sufficient to cause the float v^2 , in the chamber v^3 , to open the power throttle valve V, thereby admitting liquid pressure through the open valve p^4 , to the power pipe p , and thence to the rear of the power piston A'. Under these 35 conditions the liquid pressure acting on the rear of the power piston A', again forces said piston A', rod a , and discharge piston A, forward against the resistance of the weight w . Just prior to the completion of this forward stroke the power piston A', again contacts with and rocks the latch dogs 40

e, e against the resistance of their springs e', e' , thereby again releasing the sleeves S, and the spring s^x , so that the valves p^4 , and d' , are again reversed, and the cycle of operations above described is repeated.

It is understood of course that during the forward thrust of the pistons the liquid previously collected in the cylinder C, is driven out through the discharge pipe c^2 , and check valve c'' . It is also to be noted 70 that the float valve casing v^3 , communicates with said cylinder C, through the ducts v^4 , and v^5 , in advance of the forward limit of motion of the discharge piston A, so that there is no waste of liquid to be conserved 80 by reason of the entry of a portion thereof into the auxiliary chamber v^3 , to actuate the throttle valve V,—said liquid flowing back into the cylinder C, as the discharge piston A, recedes during the retractile 85 stroke.

It is to be understood that in showing and describing the use of a weight w , to effect the retractile movement of the pistons, &c., I wish to include any equivalent thereof, as 90 a retractile spring or any other expedient, mechanical or otherwise, arranged to derive retractile energy during and by reason of the enforced power stroke of the pistons, &c.

The component parts of my apparatus are 95 adapted to be arranged and mounted as a unit upon a common base or support so as to be readily installed or removed intact in any desired situation,—only ordinary pipe couplings being involved in connecting the 100 apparatus up for use.

It is readily adaptable for use as a device for returning water of condensation from a lower level to a higher level by means of hydraulic pressure, such as that 105 afforded by city main pressure or tank pressure,—the relative proportions of the two cylinders, pistons, &c., being such that the volume of heated water saved is much greater than the volume of water under 110 pressure sacrificed.

I do not confine myself to the conservation of water of condensation, since my apparatus may be employed advantageously in 115 various arts and industrial processes, as for the collection and return of dye water or other liquid of value to vats, &c., and anywhere where high liquid pressure is available for raising or returning liquid under 120 low pressure,—the distinctive feature of my invention being the automatic control of the apparatus whereby the collected liquid itself, under low pressure, effects its own discharge, delivery, or elevation by means of high pressure liquid indirectly through the medium of pistons and cylinders of different diameters, so that a relatively large 125 volume of liquid is conserved by the sacrifice of only a comparatively small volume of actuating liquid. Although obviously where 130

a superabundance of water under moderate pressure is available as the motive power, the power cylinder P, &c., may be as large or even larger than the collection cylinder C, without detracting materially from the economic results attained by the conservation of the liquid collected in the cylinder C.

While the use of a float for operating the power throttle is a convenient expedient for 10 enabling the collected liquid to automatically effect its own discharge, it is obvious that other mechanical equivalents and expedients may be resorted to for the purpose without departing from the spirit and intent of my invention in this respect, so that any means for automatically opening and closing the power valve which is actuated and controlled by the water level in the collecting cylinder is to be included as within 15 the scope of my invention in this respect.

It is to be understood that by the use of the term "cylinder" herein I mean to include any chamber or compartment, not necessarily but preferably annular in cross 25 section, adapted to fulfil the functions and requirements herein set forth as related to the fluid power compartment P, and the liquid collection compartment C.

What I claim as my invention and desire 30 to secure by Letters Patent is,

1. Hydraulic apparatus of the character designated, comprising a low pressure fluid collection cylinder and a high pressure fluid cylinder, pistons in said cylinders connected to operate in unison, an inlet for fluid to said collection chamber, an outlet therefor, an actuating fluid supply independent of both the inlet and outlet of the actuated fluid, a valve controlling the admission of fluid under pressure to said pressure cylinder to effect the operative thrust of the pistons, means controlled by the fluid in said collecting chamber for actuating said fluid pressure valve, and mechanically 40 actuated means for automatically releasing the fluid pressure in the pressure cylinder and for effecting the retractile stroke of the pistons, said parts being positive in their action and operable under varying conditions for the purpose described.

2. Hydraulic apparatus of the character designated, comprising a low pressure fluid collection cylinder of relatively large area and in alinement therewith a high pressure 55 fluid cylinder of relatively small area, pistons in said cylinders united by a common piston rod, an inlet for fluid to said collection chamber, an outlet therefor, an actuating fluid supply independent of both the 60 inlet and outlet of the actuated fluid, a valve controlling the admission of fluid under pressure to said pressure cylinder to effect the operative thrust of the pistons, means controlled by the fluid in the collecting cylinder for actuating said valve, and mechani-

cally actuated means connected with said pistons for automatically releasing the fluid pressure in said pressure cylinder and for effecting the retractile stroke of the pistons, said parts being positive in their action and 70 operable under varying conditions for the purpose set forth.

3. In hydraulic apparatus of the character designated, the combination of a low pressure fluid collection cylinder, a high 75 pressure fluid cylinder in alinement therewith, pistons in said cylinders united by a common piston rod, an inlet for fluid to said collection cylinder, an outlet therefor, an actuating fluid supply independent of 80 both the inlet and outlet of the actuated fluid, an inlet valve controlling the admission of fluid under pressure to said pressure cylinder, an outlet valve controlling the discharge of fluid pressure from said fluid 85 pressure cylinder, means for automatically reversing said inlet and outlet valves, a float valve controlling the supply of fluid pressure to said inlet valve and actuated by the fluid collected in said collection cylinder, and mechanically actuated means for automatically effecting the retractile stroke of the pistons, said parts being positive in 90 their action and operable under varying conditions, for the purpose set forth.

4. In apparatus of the character designated, the combination of a low pressure liquid collection cylinder, a high pressure fluid cylinder in alinement therewith, pistons in said cylinders united by a common 100 piston rod, an inlet for liquid to said collection cylinder, an outlet therefor, an inlet lever valve controlling the admission of fluid under pressure to said pressure cylinder, an outlet lever valve controlling the 105 discharge of fluid pressure from said pressure cylinder, a floating sleeve loosely mounted on said piston rod and pivotally linked to said lever valves, a spring interposed between said floating sleeve and the 110 fluid pressure piston, spring latch dogs arranged to releasably hold said floating sleeve and to be tripped by motion of said fluid pressure piston, and means for automatically effecting the retractile stroke of the 115 pistons, for the purpose described.

5. In apparatus of the character designated, the combination of a low pressure liquid collection cylinder, a high pressure fluid cylinder in alinement therewith, pistons in said cylinders united by a common 120 piston rod, an inlet for liquid to said collection cylinder, an outlet therefor, an inlet lever valve controlling the admission of fluid under pressure to said pressure cylinder, an outlet lever valve controlling the 125 discharge of fluid pressure from said pressure cylinder, a floating sleeve loosely mounted on said piston and pivotally linked to said lever valves, a spring interposed be- 130

ween said floating sleeve and the fluid pressure piston, spring latch dogs arranged to releasably hold said floating sleeve and to be tripped by motion of said fluid pressure piston, a fluid pressure throttle valve controlling the supply of fluid pressure to said inlet lever valve, a float actuating and controlling said throttle valve by means of liquid contained in said collecting cylinder, and means for automatically effecting the retractile stroke of the pistons, for the purpose described.

6. In apparatus of the character designated, a low pressure liquid collection cylinder, a high pressure fluid cylinder in alignment therewith, pistons in said cylinders working in unison, said collection cylinder having an inlet and an outlet, an inlet valve controlling the admission of fluid under pressure to said pressure cylinder, a floating sleeve loosely mounted between the pistons, and connected to said valves, a spring between said sleeve and the fluid

pressure piston, and means to releasably hold said sleeve and to be tripped by motion of said fluid pressure piston.

7. In apparatus of the character designated, a low pressure liquid collection cylinder, a high pressure fluid cylinder in alignment therewith, pistons in said cylinders working in unison, said collection cylinder having an inlet and an outlet, an inlet valve controlling the admission of fluid under pressure to said pressure cylinder, a floating sleeve loosely mounted between the pistons, and connected to said valves, a spring between said sleeve and the fluid pressure piston, means to releasably hold said sleeve and to be tripped by motion of said fluid pressure piston, and means for automatically effecting the retractile stroke of said pistons.
